ANODE CONSTRUCTION

Charles V. Litton, Redwood City, Calif., assignor
to Federal Telephone and Radio Corporation,
New York, N. Y., a corporation of Delaware

Application December 4, 1944, Serial No. 566,449

14 Claims. (Cl. 250—27.5)

1

This invention relates to electron discharge tubes and particularly to an anode construction for a high power thermionic tube, such as is used for the output stage of a carrier wave transmitter.

In high powered thermionic tubes, it is often desirable to provide some means to cool the anode and thus prevent it from overheating during the operation of the tube, and when such cooling means is used, it is preferable to provide a good heat conducting path between the cooling medium and the anode and a long enough one so as to provide a sufficient heat gradient between the anode and cooling medium to prevent overheating of the medium. The anode however is subject to expansion upon the temperature being raised and, when fluid cooling means is used, it is difficult to provide the conducting path between the cooling medium and the anode and at the same time permit the anode to expand freely with temperature changes to prevent structural strains from deteriorating the anode wall.

It is one of the objects of the present invention to provide an anode structure for a thermionic tube having a fluid cooling means which has a good heat conducting path between the cooling medium and the anode and at the same time will permit expansion of the anode with temperature changes.

Another object of the invention is to provide an anode structure for a thermionic tube having a fluid cooling means which is connected to the anode structure by a good heat conducting path but which is free to expand axially of the anode structure when the anode structure expands axially thereof so as to permit the anode structure to expand freely with temperature changes.

Another object of the invention is to provide an anode structure for a thermionic tube having a fluid cooling means in the form of a coiled tubular fluid conductor with separate heat conducting paths between the turns of the tubular fluid conductor and the anode structure to permit the turns of the fluid conductor to separate when the anode structure expands axially thereof.

Other objects of the invention will be apparent as the description thereof proceeds.

Several embodiments of the invention have

2

been illustrated in the accompanying drawings, in which:

Fig. 1 is a side elevational view, partly in section, of an anode structure incorporating one form of the invention;

Fig. 2 is a fragmentary sectional elevational view through the side wall of the anode structure of Fig. 1 illustrating the manner in which expansion takes place in the anode and the effect of such expansion on the cooling means;

Fig. 3 is an elevational view partly in section of the embodiment shown in Fig. 1 showing the parts in their expanded form;

Fig. 4 is a sectional elevational view of a slightly different form of the invention from that shown in Fig. 1 with a larger number of heat conducting rings than there are fluid conducting coils;

Fig. 5 is a side elevational view of a modified form of the fluid conducting coils shown in Figs. 1, 2 and 3;

Fig. 6 is a sectional elevational view of a modified form of the invention in which, instead of heat conducting rings, a single spiral member is provided which has substantially the same cross section as the rings.

In Fig. 1 is shown one form of the invention which may be preferred because of its simplicity and ease of manufacture. A high power thermionic tube 1, such as a transmitting tube, is shown provided with a conventional cathode and grid structure 2, indicated in dot and dash lines, and a heavy tubular anode 3 which forms the outer shell of the tube and which is sealed into a glass envelope 4 which insulates it from the supports for the other elements.

The anode 3 is circular in cross section and around it are placed a plurality of heat conducting members such as flat rings 5 of copper or other good heat conducting metal, and these rings have their inner surfaces welded or otherwise attached to the anode 3 as indicated at 6 in Figs. 1 and 2, so as to provide good heat conductivity between the inner surface of the rings and the outer surface of the anode structure. The rings are preferably placed close together in order to increase the mass of the anode and provide a greater heat conducting path from the anode to the outer surfaces of the rings.

In close contact with the outer surfaces of the

rings I provide a duct or ducts 7 for circulating cooling fluid. These ducts may take the form of a coil of metal tubing, as, for instance, copper, which is provided with suitable inlet and outlet fittings, (not shown), so that water or other cooling medium may be introduced into the inlet 8 at the top and be brought out of the outlet 9 at the bottom. The inside surfaces of the turns of the coil 7 are preferably welded to the outer surfaces of the rings 5, as indicated at 10 in Figs. 1 and 2 and by the shaded areas in Fig. 3.

In the embodiments shown in Figs. 1 to 3 the fluid conducting duct has the same vertical dimension per turn as the vertical dimension of the ring and there is one turn of the fluid conducting duct per ring. Since the fluid conductor is in the form of a coil the turns of the duct do not exactly align with the rings and there is a cross over from one ring to the next adjacent ring. Each turn of the duct therefore is welded to a particular ring for the major distance of the turn, but as the duct crosses over the crack between two adjacent rings it is left unwelded with respect to both rings. Thus, in Fig. 3 each turn 7 is welded to its associated ring for a distance around the circumference extending around the opposite side of the assembly between the dot and dash lines 11 and 12. Between these lines on the forward side of the assembly the ducts are not welded to the rings. Therefore, although the welded portion of each turn of the duct may not bend, the unwelded portion of each turn may bend slightly as the anode expands axially to permit the separation of the turns of the duct, as indicated in Fig. 3.

The temperature of the inner surface of each ring will be approximately the same as the outer surface of the anode structure and hence will expand the same amount as the anode if the two materials are the same. The metal of each ring is cooler as it approaches the outer surface where it is in contact with the cooling duct and hence will expand less and less in the axial direction of the anode as it approaches the outer surface. Therefore, the cross section of each ring when under operating conditions will assume the shape as is shown in the exaggerated form in Fig. 2 and the separate turns of the duct 7 will separate, as indicated.

While it may be preferable to have the ducts with the same dimension axially of the anode as the rings, this is not necessary, as larger ducts may be used if desired, as indicated in Fig. 4. Here, the duct 13 has a greater vertical dimension than each ring 5 and consequently there are fewer turns of the duct than there are rings. The welding of the turns of the duct to the rings is accomplished as described before, each turn being welded to the major portion of one ring, and then a space is left corresponding to the space between the dot and dash lines 11 and 12 of Fig. 3 where the duct is not welded to any ring. At this unwelded portion the duct may bend slightly so as to permit separation of the turns of the duct 13 as the anode expands and the outer edges of the rings separate. This same principal of welding the duct of the rings is followed if the turns of the duct are spaced apart so as to increase the pitch of the spiral.

In some instances it may be desirable to provide the duct, as shown in Fig. 5, with a major portion of each turn lying in the same plane as the ring and having an offset portion 15 which joins one turn of the duct with the next adjacent turn. Where this arrangement of duct is used

with rings having the same dimension in the axial direction of the anode as the duct, the major portion 14 of each turn of the duct may be exactly aligned with the ring and welded to the entire outer surface of the ring, thus making a better heat conducting joint. Where there are fewer turns of the duct than the number of rings or where the duct is provided in a true spiral, as in Figs. 1 to 3, it will not be possible to weld the entire outer surface of each ring to one of the turns of the duct, since the pitch of the duct coil necessitates an overlapping of rings and ducts.

The most practical way of making the heat conducting members is in the form of the rings, as shown in Figs. 1 to 5 inclusive. However, it may be desired to make the heat conducting members of a single piece of metal having the cross section of a ring of the previous figures and wound in a spiral 16, as shown in Fig. 6. With such an arrangement the dimension in the axial direction of the anode of both spiral heat conducting members 16 and duct 7 may be the same and the pitch may be the same, so that the outer surface of the heat conducting spiral 16 may be welded to the inner surface of the duct 7 throughout the entire length of both. This will provide an excellent heat conducting contact between the two and at the same time the turns of the coil may separate as the anode expands.

It will be seen from the above that I have provided a simple anode structure by means of which a good heat conducting path is provided between the anode and the cooling medium therefore, while at the same time movement of the anode caused by expansion under increased temperature is permitted without disturbing the heat conducting path. Strains will therefore be prevented from being set up in the anode which tend to cause structural deterioration after the anode has been in operation for a period of time.

Various modifications on the invention will suggest themselves to those skilled in the art, and I therefore do not desire to limit my invention except by the limitations defined in the appended claims.

What is claimed is:

1. An anode structure for an electron discharge tube comprising a tubular anode member, a plurality of closely positioned heat conducting ring members extending around the outside of said tubular anode member with the inner surfaces of said heat conducting members in heat conducting contact with the outer surface of said member, said heat conducting ring members having a substantially rectangular cross-section with the lesser dimension along the axis of said anode member, said ring members being placed in contact at their inner peripheries, and fluid cooling means in the form of a coil in heat conducting contact with the outer surfaces of said heat conducting ring members, said fluid cooling means being secured to said ring members for only a portion of each turn of said fluid cooling means for allowing axial expansion of said anode member and separation of said ring members.

2. An anode structure for an electron discharge tube comprising a tubular anode member, a plurality of closely positioned heat conducting ring members surrounding said tubular anode member with the inner surfaces of said heat conducting members welded to said anode member, said heat conducting ring members having a substantially rectangular cross-section with the lesser dimension extending axially of said anode member, said ring members being placed in contact

at their inner peripheries, and fluid cooling means in the form of a coil in heat conducting contact with the outer surfaces of said heat conducting members, said fluid cooling means being secured to said ring members for only a portion of each turn of said fluid cooling means for permitting axial expansion of said anode member and separation of said ring members.

3. An anode structure for an electron discharge tube comprising a tubular anode member, a plurality of heat conducting ring members surrounding said anode member with the inner surfaces of said heat conducting members in heat conducting contact with the outer surface of said anode member, said heat conducting members having a substantially rectangular cross-section with the lesser dimension in the axial direction of said anode member, said ring members being placed in contact with each other at their inner peripheries, and a duct through which cooling fluid is adapted to be circulated arranged in a coil in close heat conducting contact with the outer surfaces of said heat conducting members, said duct being secured to said ring members for only a portion of each turn of said duct for allowing axial expansion of said anode and separation of said ring members.

4. An anode structure for an electron discharge tube in accordance with claim 3, in which each individual turn of the duct for circulating the cooling fluid is attached to a separate one of said heat conducting members.

5. An anode structure for an electron discharge tube in accordance with claim 3, in which each individual turn of the duct for circulating the cooling fluid is welded to the outer surface of a separate one of said heat conducting members.

6. An anode structure for an electron discharge tube comprising a tubular anode member, a plurality of heat conducting members surrounding said anode member with the inner surfaces of said heat conducting members attached in heat conducting relation with the outer surface of said anode member, said heat conducting members having a substantially rectangular cross-section with the lesser dimension in the axial direction of said anode member, said heat conducting members being placed in contact with each other at their internal peripheries, a metal duct through which a cooling fluid is adapted to be circulated arranged in a coil surrounding said heat conducting members, each turn of said coil being welded throughout the major portion of the distance around said heat conducting members to a separate heat conducting member, there being a sufficient length of duct left unwelded in each turn at a point where said duct crosses over from one heat conducting member to another to permit bending of the unwelded portion of said duct, so as to permit the turns of the coil of said duct to separate as said anode member expands in an axial direction.

7. An anode structure for a thermionic tube comprising a tubular metal member, a plurality of metal rings surrounding said tubular member with the inner surfaces of said rings welded to the outer surface of said member, said metal rings being arranged in contact with each other at their internal peripheries, and a coil of metal tubing adapted to conduct cooling fluid surrounding said rings and having its inner surface welded to the outer surfaces of said rings, each turn of said coil being welded to one of said metal rings for only a portion of said turn for permitting axial expansion of said tubular metal member and separation of said metal rings.

8. An anode structure for a thermionic tube comprising a tubular metal member having a circular cross-section, a plurality of metal rings surrounding said tubular member with the inner surfaces of said rings welded to the outer surface of said member, said rings being arranged in contact with each other at their inner peripheries, and a coil of metal tubing adapted to conduct cooling fluid surrounding said rings and having its inner surface welded to the outer surfaces of said rings, each turn of said coil of metal tubing being welded to one of said rings for only a portion of said turn for permitting bending of the unwelded portion of each turn of said coil with axial expansion of said metal member.

9. An anode structure for a thermionic tube comprising a tubular member of copper having a circular cross-section, a plurality of closely positioned, flat, copper rings surrounding said tubular member with the inner surfaces of said rings welded to the outer surface of said member, said copper rings being arranged in contact with each other at their inner peripheries, and a coil of metal tubing adapted to conduct cooling fluid surrounding said rings and having its inner surface welded to the outer surfaces of said rings, each turn of said coil of metal tubing being welded to one of said copper rings for only a portion of said turn for permitting bending of the unwelded portion of each turn of said coil with axial expansion of said tubular member.

10. An anode structure for an electron discharge tube comprising a tubular metal anode member, a plurality of heat conducting members surrounding said tubular anode member with the inner surfaces of said heat conducting members welded to the outer surface of said member, and a coil of metal tubing adapted to conduct cooling fluid surrounding said heat conducting members, said coil being wound with each turn in a flat plane perpendicular to the axis of the coil throughout a major portion of the turn and with the remaining portion of each turn bent at an angle to said plane to connect with the next adjacent turn, the major portion of each turn which lies in said plane being welded to a separate one of said members with the remaining portion of each turn left unwelded.

11. An anode structure for a thermionic tube according to claim 10, in which the heat conducting members are metal rings and one is provided for each turn of the fluid conducting tubing.

12. An anode structure for a thermionic tube in accordance with claim 10, in which the anode member has a circular cross-section and the heat conducting members are metal rings and there is one turn of the tubing for the cooling fluid for each of said rings.

13. An anode structure for an electron discharge tube comprising a tubular anode member, a plurality of heat conducting members surrounding said anode member with the inner surfaces of said heat conducting members in heat conducting contact with the outer surface of said anode member, said heat conducting members being formed of a single bar surrounding said anode member in a helix, said bar being secured to said anode member for only a portion of each turn of said bar, and a duct through which cooling fluid is adapted to be circulated arranged in a coil in close heat conducting contact with the outer surfaces of said heat conducting members whereby faces of said heat conducting members whereby

the unwelded portion of said bar may bend with axial expansion of said tubular anode member.

14. An anode structure for an electron discharge tube in accordance with claim 13, in which the coil of the duct is wound in the same direction and with the same pitch as the helical bar.
